UNITED STATES PATENT OFFICE.

LUKE RILEY, OF SAULT STE. MARIE, MICHIGAN.

COMBINED PUNCH, SHEARS, AND SAW-GUMMER.

SPECIFICATION forming part of Letters Patent No. 416,499, dated December 3, 1889.

Application filed September 9, 1889. Serial No. 323,458. (No model.)

To all whom it may concern:

Be it known that I, LUKE RILEY, a citizen of the United States, residing at Sault Ste. Marie, in the county of Chippewa and State of Michigan, have invented certain new and useful Improvements in a Combined Punch, Shears, and Saw-Gummer, of which the following is a specification, reference being had therein to the accompanying drawings.

This invention relates to a new and useful improvement in a combined saw-gummer, shears, and punch; and the invention consists in the peculiar construction whereby the machine may be used for the different purpose of gumming saws, or, by a change of dies, as a powerful punch or shears, all as more fully hereinafter described, and shown in the accompanying drawings, in which—

Figure 1 is a side elevation showing my device as arranged for gumming saws. Fig. 2 is a plan of Fig. 1 with the upper die and lever removed to show the bed-die more plainly. Fig. 3 is a side elevation showing the device mounted as shears, and Fig. 4 is a vertical central section showing the device mounted as a punch.

A is the bed-plate of the device. B are lugs at the ends thereof as means for fastening the bed-plate by screws or bolts or otherwise upon a solid foundation.

C are two parallel guides secured transversely upon the front end of the bed-plate, or made integral therewith, if desired. The inner sides of these guides are undercut to 35 slidingly receive and hold the lower or bed-die D. This bed-die is provided upon its inner edge with indentations between the saw-teeth, there being a sufficient number of graduated sizes to adapt the bed-die for gumming different saws. This bed-die also contains a series of holes F, of graduated sizes, to use the bed-die for punching holes, as will be more fully hereinafter described.

To adjustably secure this bed-die between the guides, I use a suitable set-screw G, preferably through the front guide. In addition, the guides C are provided with recesses H opposite each other to receive and hold the stationary knife or shear I when the device

is used for shears. Between the upper ends, 50 secured to or formed integral with the bed-plate, is pivotally secured a power-lever J, the short arm of which is bifurcated and contains an anti-friction roller, which is adapted to bear at or near the free end of a lever K, 55 which is secured longitudinally between the supports near the rear end of the bed-plate, and the front end of which projects sufficiently to receive suitable dies to act in connection with the stationary dies secured upon the 60 bed-plate.

To make the dies exchangeable, I provide the lever K at its free end with a vertical socket, and the dies I provide with corresponding shanks adapted to enter the sockets 65 and be secured therein by a suitable set-screw L.

The die M for gumming saws is made of suitable shape to punch out the desired indentations between the saw-teeth, and a number of these dies are provided corresponding in size to the indentations in the bed-die.

N is a movable shear, which is also provided with a suitable shank to be secured to the lever K in proper relation to the lower knife or 75 stationary shear I, and the punch-dies O are properly constructed that when secured to the lever K they may be made to register with the holes F in the lower bed-die.

In practice, the parts being arranged as 80 shown and described, it will be seen that the device is very compact and useful for a variety of purposes, dispensing with the use of separate tools or devices for different work, the adjustment for the different purposes being quickly made.

The power-lever J is made of suitable strength and advantage of purchase to produce the necessary power for the work for which the device is designed, and by means 90 of the anti-friction wheel on the short arm of the power-lever but little force is consumed in friction.

A suitable spring K' is placed under the lever K to return it automatically into its raised position when the power-lever is thrown back, and a suitable opening P is provided in the bed-plate for the escape of the débris.

If desired, the bed-plate with the supports and guides in front may be all cast in one piece.

What I claim as my invention is—

5 The combination, with the supporting frame or base, levers K and J, and spring K', of the series of dies or anvils fixably interchangeable to the frame, and the several series of punches, gumming-punches, and shear-blades interchangeably attachable to the levers and

co-operating with the dies, all constructed and operating substantially as described.

In testimony whereof I affix my signature, in presence of two witnesses, this 18th day of July, 1889.

LUKE RILEY.
